ing through interconnected hand lever 30 and operating rod 31 to permit actuation of internally located clutch mechanism whereby, without the motor being stopped, the washing mechanism may be halted for removal of the clothes from the tub as, for instance, for wringing.

If desired, the motor and the mechanism immediately associated therewith may be hidden within a skirt 32.

It will be apparent that since drive shaft 26 extends through the bottom of tub 10 at its geometrical center, and since such shaft is rigidly attached to gear 19 and dasher 11 is mounted on its vertical axis on lug 16, which is offset from the axis of gear 19, during operation of the motor 29 in the engaged condition of the above-described clutch, unidirectional rotation in an orbital path of travel will be transmitted to the dasher. It will also be obvious that the rotation imparted to gear 20 by gear 19, with which it is intermeshed, will impart to arm 22 an arcuate reciprocatory movement which by reason of the linkage of such arm to the dasher will impart to the dasher a reciprocatory movement as it transcribes its orbit. The amount of reciprocation or oscillation imparted to the dasher may be varied in accordance with the diameter of gear 20 or the length of arm 22 and the positioning of its vertically extending lugs 18, 21 with respect to the axes of the gear or dasher. I have achieved highly excellent results, for instance, by oscillating the dasher through forward and backward arcs of around 60°.

Referring now to Figs. 3 and 4, reference numeral 110 indicates the bottom of the tub, 111 indicates the dasher and 112 indicates the dasher vanes, four of which are shown.

A vertical drive shaft 126 extends vertically through the tub 110 at its geometric center and has rigidly mounted on its upper end the eccentric 119 which carries at its end the vertically extending dasher axle 116 which is freely receivable in an appropriate bore in the dasher at the vertical axis of the latter. Axle 116 also passes through an appropriate annular hole or bore adjacent the end of a first reciprocating bar 140. Bar 140 at its end opposite its engagement with dasher axle 116 is bifurcated by a longitudinally extending slot 141, the lateral edges of which are parallel as shown. A vertically extending pivot rod 142 is rigidly mounted on the tub bottom serving the dual functions of pivot and guide for bar 140 during its arcuate reciprocation as dasher 111 transcribes its orbit.

Spaced from the slotted end of bar 140 is pivotally mounted at 148 one end of a swinging link 143 which is provided with an internal slot 144, the lateral edges of which are parallel, as shown. A vertically extending pivot rod 145, like in form, mounting and purpose to similar rod 142, is engaged with slot 144. At its end opposite its connection 146 to bar 140, designated 147, link 143 is pivotally connected to a second reciprocating bar 148 which at its end opposite its connection to link 143 is pivotally connected to dasher 111 on a pivot 149 at a point radially offset from the axis of such dasher.

It will be obvious from the foregoing description of the structure of Figs. 3 and 4 that as eccentric 119 rotates carrying with it dasher 111, the dasher is moved in an orbital path of travel. Arcuate reciprocatory movement will then be transmitted to first reciprocating bar 140 which will be guided and pivoted during its arcuate reciprocation on pivot rod 142. Bar 140 during its reciproca-

tion will transmit reciprocation to link 143 which in its reciprocation will be guided and pivoted on second pivot rod 145 by means of cooperating slot 144. Due to its connected relation to link 143 second reciprocating bar 148 will be given a reciprocating movement which, due to its pivotally connected relation to dasher 111, will be positively reciprocated within predetermined limits as it transcribes its annular orbit.

As hereinbefore indicated, this multiple combined movement of the dasher does a far better job of washing than does a unidirectionally travelling dasher which merely transcribes an orbit and in which the reciprocatory movement, if any, of the dasher is random, impositive, unpowered, or unpredicted. I attribute the enhanced results to the additional agitation imparted to both the water and the clothes and to some degree to the increased rubbing action engendered by the combined movements of the dasher.

Having shown and described my invention in considerable detail, I do not wish this exactness of disclosure to be taken in a limiting but rather in an illustrative sense, desiring to be limited only by the scope of the appended claims.

I claim:

1. In a washing machine having a tub; a dasher mounted in the bottom of the tub and extending above the water line of the tub; power driven means for imparting circular bodily movement to said dasher in an orbital path about a fixed axis within said tub; and power driven means for imparting oscillatory movement to said dasher as it transcribes its orbit, said last-named means including, at least one movable element offset with respect to the axis of said dasher and a link connected in a reciprocating relation to the dasher.

2. In a washing machine having a tub; a dasher; means for imparting circular movement to said dasher in an orbital path within said tub; and means for imparting oscillatory movement to said dasher as it transcribes its orbit, said last-named means including a rotating element offset with respect to the axis of said dasher and a link, one end of the latter being connected in non-axial relation to said rotating element and the other end being connected to said dasher in non-axial relation thereto.

3. In a washing machine having a tub; a dasher; means for imparting circular movement to said dasher in an orbital path within said tub; and means for imparting oscillatory movement to said dasher as it transcribes its orbit, said last-named means comprising a pair of intermeshed gears driven during rotation of said dasher and a link, one end of which is connected in non-axial relation to one of said gears and the other end of which is connected to said dasher in non-axial relation thereto.

4. In a washing machine having a tub; a dasher drive shaft; a dasher; means for imparting circular movement to said dasher in an orbital path within said tub; and means for imparting oscillatory movement to said dasher as it transcribes its orbit, said last-named means comprising a horizontally disposed gear attached to said dasher drive shaft, a second gear meshed with said first-mentioned gear in offset relation to the axis of said dasher drive shaft, and a link interconnecting said second gear and said dasher, said link being connected with said second gear and said dasher in non-axial relation to each.

5. In a washing machine having a tub; a dasher drive shaft having an eccentric member; a

dasher axially mounted on said eccentric member eccentrically relative to the drive shaft; means for imparting circular movement to said dasher in an orbital path within said tub; and means for imparting oscillatory movement to said dasher as it transcribes its orbit; said last-named means comprising a first reciprocating element, one end of which is attached to said eccentric member and the other end of which is guided for reciprocation, a second reciprocating element, a pivoted link interconnecting one end portion of said first reciprocating element and one end of said second reciprocating element, the other end of said second reciprocating element being connected to said dasher in offset relation to the axis thereof.

6. In a washing machine having a tub, a drive shaft, a dasher surrounding said shaft and journaled for rotation relative to said shaft and the tub, said shaft being connected with the dasher eccentrically of the shaft for moving the dasher bodily in an orbit relative to the axis of the shaft, and means operatively connected with the dasher for causing oscillatory movement thereof during movement through said orbit, said means including a link connection with the dasher and means for reciprocating said link.

7. In a washing machine having a tub, a drive shaft, a dasher surrounding said shaft and journaled for rotation relative to said shaft and the tub, said shaft being connected with the dasher eccentrically of the shaft for moving the dasher body in an orbit relative to the axis of the shaft, and means operatively connected with the dasher for causing oscillatory movement thereof during movement through said orbit, said means including a link pivoted at one end portion thereof to the dasher and having means connected with the opposite end portion thereof for causing reciprocating movement of said link during movement of the dasher through the orbit.

8. In a washing machine having a tub, a drive

shaft, a dasher surrounding said shaft and journaled for rotation relative to said shaft and the tub, said shaft being connected with the dasher eccentrically of the shaft for moving the dasher bodily in an orbit relative to the axis of the shaft, and means operatively connected with the dasher for causing oscillatory movement thereof during movement through said orbit, said means including a link connection with the dasher, and intermeshing gears, one of which is fixed to the drive shaft and the other has a pivotal connection with said link eccentrically of the last-mentioned gear.

9. In a washing machine having a tub, a drive shaft, a dasher surrounding said shaft and journaled for rotation relative to said shaft and the tub, said shaft being connected with the dasher eccentrically of the shaft for moving the dasher bodily in an orbit relative to the axis of the shaft, means operatively connected with the dasher for causing oscillatory movement thereof during movement through said orbit, said means including a link connection with the dasher and means for reciprocating said link, including a second link pivotally connected with the first-mentioned link at adjacent end portions and spaced from the connection with the dasher, and means for moving said second link about an axis fixed relative to the dasher.
